Des. 210,524
Patented Mar. 19, 1968

210,524

BURIAL VAULT

Guy Smith, 217 Patricia Drive, Forest Park, Ga. 30050

Filed May 4, 1966, Ser. No. 2,154

Term of patent 14 years

(Cl. D19—1)

Fig. 1

Fig. 2

Fig 4

Fig 5

Fig 3

FIG. 1 is a top perspective view of a burial vault embodying my new design;

FIG. 2 is a bottom perspective view thereof;

FIG. 3 is a top plan view thereof;

FIG. 4 is an end view thereof; and,

FIG. 5 is a cross-sectional view taken along line 5—5 in FIG. 3.

I claim:

The ornamental design for a burial vault, as shown.
